UNITED STATES PATENT OFFICE

99,377

DESIGN FOR A ROSARY

Joseph F. Stedman, Brooklyn, N. Y.

Application February 24, 1936, Serial No. 61,325

Term of patent 14 years

To all whom it may concern:

Be it known that I, Joseph F. Stedman, a citizen of the United States and a resident of Brooklyn, in the county of Kings and State of New York, have invented a new, original, and ornamental Design for a Rosary, of which the following is a specification, reference being had to the accompanying drawing, forming part thereof.

Figure 1 is a front elevational view of a rosary, showing my new design.

Figure 2 is an enlarged front elevational view of a portion of the rosary.

Figure 3 is an edge elevational view of that portion shown in Figure 2.

Figure 4 is a detail vertical sectional view through one of the beads and taken on the line 4—4 of Figure 3 thereof.

I claim:

The ornamental design for a rosary, as shown.

JOSEPH F. STEDMAN.
